UNITED STATES PATENT OFFICE.

HENRY W. PLEISTER, OF WESTFIELD, NEW JERSEY, ASSIGNOR TO HENRY B. NEWHALL.

BOLT-ANCHOR.

1,248,006.

Specification of Letters Patent. Patented Nov. 27, 1917.

Original application filed September 20, 1916, Serial No. 121,104. Divided and this application filed January 20, 1917. Serial No. 143,425.

To all whom it may concern:

Be it known that I, HENRY W. PLEISTER, a citizen of the United States, residing at Westfield, in the county of Union and State 5 of New Jersey, have invented certain new and useful Improvements in Bolt-Anchors, of which the following is a specification, taken in connection with the accompanying drawings.

10 This application is a division of my co-pending application Ser. No. 121,104 filed Sept. 20, 1916, for improvements in bolt anchors.

My invention relates to bolt anchors.

15 In the present form of bolt anchors the maximum expansion is approximately at the extreme inner end of the anchor. In practice this is often a serious detriment in that the screw or other expanding member, 20 having forced the bolt anchor out to its maximum expansion, binds and it is impossible to bring the head of the bolt or screw up flush with the work. This requires that the hole be enlarged entailing additional 25 labor and expense, or that a different size bolt anchor be used.

By my invention I overcome this serious objection and give a longer surface of maximum contact or grip on the exterior 30 of the bolt anchor, thereby giving an increased frictional hold and distributing this maximum grip over a larger area than with the present forms. My invention further permits the screw or bolt to coöperate 35 with the bolt anchor with less effort, than in the present forms.

My invention further relates to certain details of construction which will be described in the specification and pointed out 40 in the claims.

I have shown in the accompanying drawings an illustrative embodiment of my invention but of course it is to be understood that my invention is not to be confined 45 simply to the form illustrated except as required by the scope of the appended claims. In these drawings the same reference numeral refers to similar parts in the several figures.

50 Figure 1 is a vertical longitudinal section through a one-part bolt anchor known as a one part lag shield;

Fig. 2 is a vertical section through the one part shield shown in Fig. 1, the sup-

port and the work supported, the lag screw 55 being in side elevation;

Fig. 3 is a longitudinal vertical section showing the bolt anchor holding work of a different thickness from that shown in Fig. 1;

Fig. 4 is a longitudinal vertical section through a one part bolt anchor, known as a one port lag shield, provided with weakening portions;

Fig. 5 is a vertical section through the 65 one part lag shield shown in Fig. 4, the support, and the work supported, showing the coöperating lag screw in side elevation.

In the illustrative embodiment of my invention, 1 is a one part lag shield having 70 an open side 2 permitting the lag screw 3 to engage directly with the inclined surface 4 and the cylindrical surface 5 of the lag shield and also directly with the wall 6 of the hole 7 in the support 8.

I preferably provide my lag shield with lugs 9, 9. The inclined surface 4 merges about at the point 10 with the cylindrical surface 5.

In the form of lag shield now on the 80 market, the bore has an inclined substantially uniform taper extending from near one end to the other end of the shield. In coöoperating with a lag screw, such as 3, the maximum expansion in the old form is 85 approximately at the end of the old lag shield.

In my present invention the lag shield is provided with an open throat 11 which so far as the expansion is concerned is neutral, 90 in that there is no expansive coöperation between the open throat and the lag screw 3. Not until the lag screw engages the inclined surface 4 does the lag shield begin to expand or positively grip that portion 95 of the wall of the support 8 lying adjacent to it. This expansion continues until the lag screw 3 has reached the point 10 when it will travel along the cylindrical, or semi-cylindrical, surface 5, with the same expansive power or force that it developed 100 at the point 10 until the end 12 of the lag shield is reached.

The maximum expansion therefore instead of being, as in the old form at the 105 extreme inner end 13 of the lag shield, will be distributed between substantially the points 13 and 14. It is understood of course,

that the relative length of the inclined surface 4 and the cylindrical surface 5 may be varied as found desirable; this would, of course, vary the relative length of the 5 distance between the points 13 and 14.

In holding the work 15 against the face 16 of the support 8, the male threads 17, 17 of the lag screw 3 coöperate with the female threads 18, 18 of the lag shield 1 10 and bite into that portion of the surface 6 of the hole 7 which is not covered by the lag shield.

In Fig. 3 I have illustrated the work 19 of greater thickness held by the same lag 15 screw 3 and lag shield 1. With such work, as well as with work of the thickness of the work 15, the head of the lag screw can be instantly brought up flush against the work without the screw jamming in the lag 20 shield in a position where its head 20 cannot be brought up snugly against the work. This is due to the fact that the point of maximum expansion is extended over a relatively large portion of the surface of 25 the lag shield so that the end of the screw can be brought anywhere along the cylindrical surface 5, or past the end 12 of the lag shield, as may be found necessary, to bring the head 20 flush against the work and 30 at the same time obtain the requisite maximum expansion of the lag shield. In the old form where the expansion is at the end of the shield, the lag screw would, as previously noted, often jam at that point 35 before its head was brought up flush against the work requiring the removal of the lag shield and the enlargement of the hole, or the use of a different size lag shield.

Preferably the wall of the shell is thin 40 at the point 21 and increases uniformly in thickness to a point, as for example 10, intermediate its extremities, and from that point the thickness of the shell continues with a uniform maximum thickness to the 45 end 12.

It will be seen that when the expanding means coöperates with the axial bore, said bore is distorted into a substantially true cylindrical bore thereby distorting the forward exterior cylindrical surface of the bolt anchor into a frustum of a cone, which merges into the cylindrical exterior of the outer end of the bolt anchor.

In some cases to permit the more ready 55 bending or expansion of the lag shield 23, Figs. 4 and 5, I provide it with weakening portions 24, in any suitable manner, preferably located adjacent to the point of nearest approach to the axis of the inclined surface 25.

In these figures, the lag shield 23 is provided with an open throat 26 and with an inclined surface 25 reaching its nearest approach to the axis at the point 27, and then merging into the parallel or semi-cy-

lindrical surface 28. The lag shield is preferably provided with the female screw-threads 29 and also preferably with one or more lugs 30. The weakening portion 24 is formed by casting valleys 31 which, 70 as previously noted, for best results, should be located adjacent to the point 27 of the inclined surface 25.

In this form the lag screw 3 coöperates 75 with the inclined surface 25 and the semi-cylindrical surface 28 and also with that portion 6 of the wall of the hole 7 in the support 8 which is not covered by the lag shield 3.

Having thus described this invention in 80 connection with an illustrative embodiment thereof, to the details of which I do not desire to be limited, what is claimed as new and what is desired to secure by Letters Patent is set forth in the appended claims: 85

1. A bolt anchor comprising an expansible member having an open side provided with a tapering surface ceasing intermediate its length and then merging into a surface substantially coaxial with the anchor. 90

2. A bolt anchor comprising an expansible member having an open side provided with a surface, said surface inclined longitudinally to the longitudinal axis to a point intermediate its ends, thence extending substantially coaxial with the anchor, and a rotative member adapted to engage said tapering surface and a portion of the surface of the hole in which the bolt anchor is located. 95

3. In a bolt anchor the combination of an expansible member having an open throat and an open side provided with a tapering surface ceasing intermediate its length and with a surface extending substantially coaxial with the anchor, and a rotative member adapted to engage said tapering and coaxial surfaces and a portion of the surface of the hole in which the bolt anchor is located. 105

4. In a bolt anchor the combination of an expansible member having an open side provided with a tapering screw-threaded surface ceasing intermediate its length and merging into a surface substantially coaxial with the bolt anchor, and a screw adapted to engage both said tapering and coaxial surfaces and the surface of the hole in which the bolt anchor is located. 115

5. In a bolt anchor the combination of an expansible member having an open side provided with a tapering surface ceasing intermediate its length and merging into a cylindrical surface, one or more lugs, and a rotative member adapted to engage both said tapering and cylindrical surfaces and the surface of the hole in which the bolt anchor is located. 120

6. A bolt anchor comprising an expansible member having an open side provided 130

with a tapering surface ceasing intermediate its length and merging into a cylindrical surface, and provided with one or more lugs.

5 7. A bolt anchor comprising a cylindrical shell having an open side provided with a concave surface, the wall of the shell being thinnest near its outer end and increasing in thickness uniformly to a point intermediate its extremities and thence continuing with substantially uniform maximum thickness to the opposite end.

10 8. In a bolt anchor the combination of an expansible member having an open side and

a weakening portion, said open side provided with a tapering surface for part of its length, and merging into a cylindrical surface substantially coaxial with the rotative expanding member, and a rotative member adapted to engage both said tapering and cylindrical surfaces and the surface of the hole in which the bolt anchor is located.
